CLAIM

We claim the ornamental design for a clip on glasses for watching 3D image, as shown and described.

DESCRIPTION

FIG. 1 is a perspective view of a clip on glasses for watching 3D image showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view in a state of use thereof; and,

FIG. 9 is a perspective view in a folded state thereof.
